UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

ANTIFRICTION BEARING

Application filed July 27, 1928. Serial No. 295,651.

This invention relates to anti-friction bearings.

One object of the invention is to provide a simple and efficient anti-friction bearing, adapted especially for use as a side bearing member for railway cars, including an anti-friction element interposed between the body and truck bolsters of the car and supported at all times on the truck bolster, wherein means is provided for centering the anti-friction element after each actuation thereof, the centering means being so designed that its operation is not affected by relative adjustment in height of the truck and body bolsters.

Another object of the invention is to provide a side bearing, including an anti-friction element supported entirely on the truck bolster and having rolling movement thereon, together with gravity-actuated centering means for the anti-friction element supported from the body bolster, wherein the centering means is automatically adjustable to accommodate itself to relative adjustments in height of the body and truck bolster.

A more specific object of the invention is to provide a side bearing for railway cars, including an anti-friction roller element supported entirely by the truck bolster, a support fixed to the body bolster provided with a bearing plate cooperating with the anti-friction roller, and a gravity-actuated centering means guided in a vertical path by the support, the centering means having inclined guide tracks cooperating with trunnions on the roller for centering the same.

Other and further objects of the invention will more clearly appear from the description and claims hereinafter following.

In the drawing, forming a part of this specification, Figure 1 is a transverse sectional view through portions of the body and truck bolsters of a railway car, illustrating my improvements in connection therewith. Figure 2 is a vertical longitudinal sectional view through the bolsters, corresponding substantially to the line 2-2 of Figure 1. And Figure 3 is a horizontal sectional view,

corresponding substantially to the line 3-3 of Figure 1.

In said drawing, 10 designates the bottom portion of a section of the body bolster of the railway car, and 11 designates a portion of the top of a section of the truck bolster which cooperates with the body bolster. As shown, the truck bolster 11 is provided with a flat top bearing surface 12 with which the anti-friction bearing cooperates.

In carrying out my invention, the anti-friction bearing element is interposed between the body and the truck bolsters. My improved anti-friction bearing comprises, broadly, an anti-friction roller element A, a carrier member B secured to the body bolster, and a centering slide C guided by the carrier member.

The anti-friction roller A is provided with a pair of centering trunnions 13-13 formed integral therewith. The centering trunnions, as shown, are in alignment with the central axis of the roller. The roller A is supported directly on the bearing surface 12 of the truck bolster 11 and is adapted to roll thereon to either side of the central position shown in Figure 1.

The carrier member B is in the form of a casting having laterally projecting securing lugs 14-14 at opposite sides thereof, by which it is supported from the body bolster 10. The lugs may be secured in any suitable manner and are herein shown as fixed by rivets extending through the same and the bottom plate of the body bolster. The casting B is provided with vertically disposed guide openings 15-15 at the opposite sides thereof, the guide openings 15 being provided with downwardly diverging end walls 16-16 at the bottom thereof, adapted to accommodate a portion of the centering slide C, as hereinafter more specifically pointed out. The guide openings 15 are provided with spaced, vertically disposed, central, interior ribs 17-17, which provide a vertical guideway 18 therebetween. The guideway 18 opens into that portion of the guide opening 15 which has the downwardly diverging walls 16.

The central portion of the casting B, which

is designated by 19, is offset upwardly with respect to the lower edge of the casting B proper, as most clearly shown in Figure 2, and has a steel bearing plate 20 secured to the bottom face thereof, the bearing plate 20 being secured in any suitable manner and being herein shown as riveted to the part 19, the latter being recessed, as indicated at 21, so as to render the rivets accessible. As clearly indicated in Figures 1 and 3, the bearing plate 20 is of greater length than the bottom face of the section 19 of the casting and has the opposite ends thereof disposed in horizontal slots 22-22 provided at the opposite ends of the supporting casting B.

The centering slide C comprises a main portion composed of longitudinally extending side wall members 23-23 and transverse end wall members 24-24 formed integral with the side wall members. At the opposite sides, the centering slide is provided with upstanding guide plate members 25-25 formed integral with the side wall sections 23. As clearly shown in Figure 3, each guide plate section 25 is provided with a central, vertically disposed rib 26 which engages between the ribs 17 of the corresponding guideway of the casting B, so as to be guided for vertical movement within the guideway 18. The plate section 25 is of such a thickness as to be guided between the free ends of the ribs 17 and the opposed side wall of the guide opening 15. As shown, each of the guide plate sections is of such a width as to fit between the end walls of the guide opening 15. As will be evident, each guide plate section is thus guided for true vertical movement in the guide openings 15 and the guideways 18. The side wall sections 23 of the centering slide C are arched centrally, as shown most clearly in Figure 1, thereby providing downwardly diverging guide tracks 27-27 which are of substantially inverted V-shape. At the junction of the diverging guide tracks, the bottom edge of the arched section of each side wall is curved, as indicated at 28, to conform to the curvature of the corresponding trunnion 13 of the roller A. At the lower ends of the diverging guide tracks, the edge portions of the side walls of the centering slide are rounded off, as indicated at 29-29, thereby providing limiting stop shoulders which cooperate with the trunnions of the anti-friction roller to limit the lateral displacement thereof.

Upon reference to Figure 1, it will be seen that the parts are so proportioned that the anti-friction roller A will also be limited by engagement with one of the transverse end walls 24 of the centering slide C when the trunnions 13 engage the limiting shoulders 29 at the corresponding end of the centering slide. The arched sections of the side walls present upwardly converging inclined surfaces 30-30 to correspond with the inclined

walls 16 of the casting B. It will be evident that when the slide C is raised to the dotted line position shown in Figure 1, the arched sections of the side walls will be accommodated within the opening between the diverging walls 16 of the casting B. The slide C is relatively heavy so that it will return to its lowered position through the action of gravity and thereby effect return of the anti-friction roller A to centered position by engagement of the trunnions 13 of the roller with inclined guide track 27 of the centering slide.

As will be evident, the roller A is supported at all times on the bearing surface 12 of the truck bolster, the slide C in no way supporting or carrying the anti-friction roller.

At times it is found necessary to adjust the relative heights of the body and truck bolsters of a railway car and shims are often inserted between the parts of the center bearing of the car to produce this adjustment. It is also common to remove such shims as necessary to bring the body and truck bolsters closer together. By the use of my improved bearing, the body and truck bolsters may be relatively adjusted without in any way affecting the proper functioning of the centering means of the improved side bearing, inasmuch as the centering means is automatically adjustable in height as the truck and body bolsters are adjusted.

The centering slide C being supported entirely upon the trunnions of the anti-friction roller and the roller bearing directly on the truck bolsters, any relative adjustment of the body and truck bolsters toward each other will not change the relative spacing between the centering slide C and the truck bolster bearing surface 12 in the normal centered position of the parts, the adjustment taking place between the centering slide and the supporting member B, the guide plate sections 25 of the centering slide C being freely movable in the guideways of the member B.

In the operation of my improved side bearing, when the body and truck bolsters are swung one with respect to the other and approach each other, the bearing plate 20 will be brought into engagement with the top of the anti-friction roller element A and the weight of the body of the car will be supported by the anti-friction roller on the bearing surface 12 of the truck bolster. During the lateral swinging movement referred to, the anti-friction roller A will roll laterally between the bearing surfaces of the body and truck bolsters until the bolsters again return to their normal position or are separated. The extreme position of movement to one side of the centered position of the anti-friction element A is shown in dotted lines in Figure 1. During the movement to one side of the centered position of the anti-friction roller

A, the trunnions 13 will roll on the corresponding inclined guide tracks of the centering slide C, thereby causing the slide to be raised against the action of gravity. Movement of the roller will be limited by the trunnions 13 engaging the stop shoulders 29 at the corresponding end of the centering slide.

As hereinbefore pointed out, the parts are also so proportioned that the roller itself will engage one of the end walls 24 of the centering slide C at approximately the same instant that the trunnions engage the stop shoulders 29, so as to limit the displacement of the roller from its normal centered position.

When the bolsters are separated so that the weight is removed from the anti-friction roller element, the slide will move downwardly, due to the influence of gravity, and, by engagement of the trunnions 13 with the inclined guide tracks 27 of the centering slide, the anti-friction roller element A will be returned to its normal centered position, as shown in full lines in Figure 1.

While I have herein shown and described what I consider the preferred manner of carrying out my invention, the same is merely illustrative and I contemplate all changes and modifications which come within the scope of the claims appended hereto.

I claim:

1. In an anti-friction bearing for railway cars, interposed between the body and truck bolsters of the car, the combination with an anti-friction element always supported on the truck bolster; of means for centering said anti-friction element supported at all times on said anti-friction element, and guided for vertical movement on said body bolster, said centering means being automatically adjustable toward and away from the body bolster to correspond with relative adjustments in height of the body and truck bolsters.

2. In an anti-friction bearing for railway cars, interposed between the body and truck bolsters thereof, said bolsters having opposed bearing surfaces, the combination with an anti-friction element always supported on the bearing surface of said truck bolster; of a guide member fixed to the body bolster; a centering member guided for vertical movement by said guide member, said centering member being provided with downwardly diverging guide tracks; and means on said anti-friction element cooperating with said guide tracks to effect centering of the anti-friction element after each actuation thereof, said centering member being at all times supported by said last named means, whereby automatic adjustment is provided between said centering member and body bolster corresponding to relative adjustments in height of the body and truck bolsters.

3. In a side bearing for railway cars provided with body and truck bolsters, the com-

bination with an anti-friction roller supported entirely on the truck bolster, said roller being provided with trunnions; of a carrier member fixed to the body bolster, said supporting member having a bearing surface opposed to the bearing surface of the truck bolster; and a weighted centering slide guided on said carrier member for vertical movement, said guide having spaced side wall members and connecting end wall members, said side wall members presenting downwardly diverging guide tracks provided with limiting shoulders, said roller trunnions cooperating with the guide tracks to effect centering of the roller when the load is removed therefrom after each actuation of the anti-friction bearing, said limiting shoulders limiting the displacement of the roller from its centered position.

4. In a side bearing for railway cars, provided with body and truck bolsters, the combination with an anti-friction roller supported entirely on the top bearing surface of the truck bolster; of a carrier fixed to the body bolster; and a weighted centering slide guided on said carrier for vertical movement, said slide being provided with an arched central section presenting downwardly diverging guide tracks, said anti-friction roller being provided with trunnions cooperating with said guide tracks, and said centering slide being provided with transverse connecting end wall sections forming limiting stop means cooperating with the roller to limit its displacement from the normal centering position.

5. In a side bearing for railway cars provided with body and truck bolsters, said truck bolster having a bearing surface, the combination with an anti-friction roller supported entirely on the bearing surface of the truck bolster, said roller being provided with centering trunnions; of a bearing member fixed to the body bolster, said bearing member having a bearing surface opposed to the bearing surface of the truck bolster; guide means on said bearing member; and a weighted centering slide guided with respect to the body bolster for vertical movement, by said guide member, said slide including side members and connecting end members, said side members presenting downwardly diverging guide tracks cooperating with the trunnions of the roller to center the same after each actuation thereof and support said slide at all times on said trunnions, said slide being held spaced from the truck bolster a fixed distance in a normal centered position of the bolsters by the roller trunnions in all positions of adjustment of said bolsters toward and away from each other.

6. In a side bearing for railway cars having body and truck bolsters provided with opposed bearing surfaces, the combination with an anti-friction roller element supported for rolling movement entirely on the

bearing surface of the truck bolster, said roller having centering trunnions; of a guide member fixed with respect to the body bolster; and a vertically slideable centering slide guided by said guide member, said centering slide being supported entirely by the anti-friction roller element and having side walls enclosing said anti-friction roller element, said side walls being cut away on the under-
5 side to provide V-shaped centering bracket members cooperating with the trunnions of the anti-friction roller element.

7. In a side bearing for railway cars provided with body and truck bolsters having
15 opposed bearing surfaces, the combination with an anti-friction roller supported entirely on the bearing surface of the truck bolster, said roller having trunnions; of a weighted centering member provided with
20 downwardly diverging guide tracks engaging said trunnions and supporting the centering member entirely at all times on said trunnions, said centering member being provided with upstanding, spaced guide arms;
25 a guide member fixed to the body bolster, said guide member being provided with vertical guideways receiving said guide arms for vertical sliding movement; and a bearing plate secured to said guide member in opposed relation to the bearing surface of the truck bolster and forming the bearing surface of the body bolster and cooperating with said anti-friction roller when the bolsters approach each other.
30

35 In witness that I claim the foregoing I have hereunto subscribed my name this 25th day of July, 1928.

JOHN F. O'CONNOR.
